UNITED STATES PATENT OFFICE.

JEAN EDOUARD ANDREAU, OF PARIS, FRANCE.

APPARATUS FOR SYNCHRONIZING CINEMATOGRAPH PROJECTIONS WITH MUSIC, SINGING, OR THE LIKE.

Application filed June 3, 1920. Serial No. 386,240.

To all whom it may concern:

Be it known that I, JEAN EDOUARD ANDREAU, a citizen of the French Republic, and a resident of 39 Boulevard Montparnasse, 5 Paris, France, have invented new and useful Improvements in an Apparatus for Synchronizing Cinematograph Projections with Music, Singing, or the like, of which the following is a specification.

10 This invention relates to means for synchronizing cinematograph projections with music, singing or the like. In known arrangements of this kind, attempts have been made to effect the synchronization by means 15 of devices affecting the motor of the cinematograph apparatus. By reason of the inertia of the revolving parts of the motor, there always occurs a break or variation between the moment at which the device 20 comes into operation and that at which the desired alteration of speed is obtained, so that it has not hitherto been possible to effect satisfactory synchronization.

25 The arrangement according to the present invention allows these drawbacks to be avoided, by effecting the synchronization by remote control of the cinematograph without interference by the motor, which continues to rotate at its normal speed; this 30 obviates disturbances due to the inertia of the revolving parts of the motor and moreover obtains the variation of the rate of speed in an almost instantaneous manner. This condition is essential for allowing the 35 film to be fed or advanced in time with the music or singing, so as to correct any disturbances arising from inconstant driving current, variation in the resistance of the film, irregularity of the motion when 40 taking the pictures, desired or accidental variations in the tempo of the orchestra, or other causes.

The improved arrangement consists in 45 interposing, between the motor and one of the parts transmitting the motion of the latter to the cinematograph apparatus, a transmission device adapted to afford a driven speed which varies automatically in inverse proportion to the mechanical resistance to be overcome, while the motor revolves constantly at its rated or normal speed whatever be the intensity of the resistance.

By subjecting one of the parts driven

by this transmission device, or one of the driven members of the transmission itself, to the action of the controlled brake, while the speed of rotation of the motor remains constant, the resistance couple of the apparatus may be increased or decreased at will, thus decreasing or increasing the speed of operation of the apparatus, and so ensuring synchronization and in a general way all desired variations of speed or relation.

The transmission may be of the type described in my prior U. S. application Serial Number 301,511, filed June 3, 1919, in which the driving shaft is connected to the driven shaft by a planetary gear provided with eccentric masses which, under the action of centrifugal force, exert on the driven shaft reactions which are utilized for driving the latter shaft.

A form of carrying out the present invention, is represented diagrammatically by way of example, upon the accompanying drawings, in which:—

Figure 1 is an elevation showing a cinematograph provided with an arrangement according to the present invention, in which the braking action is effected by an electromagnetic brake operating upon the disc of the rotary shutter of the apparatus.

Figure 2 is a partial side view corresponding to Figure 1.

Figures 3 and 4 show modifications of the braking device.

Fig. 5 is a vertical section through the transmission gear.

The electric motor *a*, instead of actuating the movement of the cinematograph apparatus directly, is connected to this movement by means of a centrifugal transmission *b* similar to that described in my U. S. application Serial Number 301,511, filed June 3, 1919. Upon the driven shaft *c* of this transmission is keyed a pulley *d*, which by means of a belt *e* operates the pulley *f* upon the shaft carrying the shutter disc *g* of the cinematograph. The disc, which is formed of sheet metal or the like, perforated or cut away in any suitable manner, is provided at its periphery with a continuous portion *g*¹ without any excisions or notches, this portion revolving between the poles *h* of an electromagnet through which a current of greater or less intensity may be passed, the regulation being effected

by means of a continuous current rheostat i located at a distance.

A centrifugal transmission gear of the type above mentioned is shown on an enlarged scale in Fig. 5. In the form illustrated, it comprises an internally toothed gear wheel b^2 keyed to the motor shaft b^1 and meshed with satellite pinions b^3 mounted freely on studs b^4 carried by the driven member c . Each satellite pinion b^3 carries an eccentric mass b^5 which rotates therewith. The eccentric masses, during the rotation of the pinions, create (by centrifugal action) thrusts in opposite directions on the studs b^4 . The thrusts in one direction only, however, are utilized to drive the member c since the latter is mounted on the frame b^7 through a one way clutch bearing b^6 (of the type commonly employed for bicycle wheels) and the frame absorbs the thrusts of the eccentricities in the opposite or negative direction. Thus, if the motor a rotates at constant speed, and exerts a constant couple on the driving shaft b^1 , then the slower the rotation of the driven member c (by reason of the resistances applied thereto) the greater the speed of rotation of the pinions b^3 and their eccentric masses b^5 . Consequently the centrifugal force reactions resulting from this increased speed of rotation, are intensified. By this form of transmission, a constant speed motor with constant driving couple, may be utilized to rotate a driven member at variable speed in accordance with a variable resistance applied thereto.

The disc revolving in the field of the electromagnet encounters a resistance to its motion proportional to the strength of the current, that is to say, it receives a braking action which is more or less energetic according to the intensity of the current as controlled from a distance by the rheostat i .

The latter is so located as to allow a person listening to the musical reproduction to regulate the travel or feed of the film in accordance with the music. The rheostat may with advantage be placed within reach of the conductor of the orchestra. It may be provided with a dial having inscriptions of any useful indications, for example, a metronome scale, the same being also inscribed upon the base plate. An adjustable zero may also be provided for daily regulation, to compensate for the greater a priori causes of inaccuracy, thus leaving only the secondary factors and reducing to a minimum the operations of the rheostat.

The electromagnetic brake may be replaced by any other suitable construction, for example, a shoe-brake j having the shoe bearing upon the periphery of the shutter disc (Figure 3) or upon any revolving part. This brake may be controlled from a distance by means of a solenoid j^1 , acting

upon a soft iron core j^2 , returned by a spring j^3 and secured to the extremity of the brake lever.

Alternatively the brake may consist of a fan-wheel k mounted upon the spindle of the shutter for example, and provided with vanes k^1 which can be feathered or turned aside to a greater or less extent. The vanes are displaced by connecting rods k^2 attached to the stem k^3 , which terminate in a soft iron core k^4 exposed to the action of a solenoid k^5 . The more strongly the core k^4 is attracted by the solenoid, the less the resistance offered by the feathered vanes to the rotation of the fan wheel, and the less energetic therefore the braking action.

It will be evident that the invention is not limited to these forms of construction which have been indicated merely by way of example, and that it may be carried out by any suitable means affording the same result.

What I claim is—

1. In combination with a cinematograph, a constant speed driving motor, and an operative connection therefrom to the cinematograph apparatus, said connection comprising transmission gear automatically varying the driven speed with the load, said transmission gear comprising a gear wheel directly connected with the constant speed motor, planetary gears meshing therewith and carried by a driven member, together with eccentric masses rotating with said planetary gears and exerting a torque on said driven member under the action of centrifugal force, in combination with means for varying the load.

2. In combination with a cinematograph, a constant speed driving motor, and an operative connection therefrom to the cinematograph apparatus, said connection comprising transmission gear automatically varying the driven speed with the load, said transmission gear comprising a gear wheel directly connected with the constant speed motor, planetary gears meshing therewith and carried by a driven member, together with eccentric masses rotating with said planetary gears and exerting a torque on said driven member under the action of centrifugal force, in combination with manually controlled means for varying the load.

3. In combination with a cinematograph, a constant speed driving motor, and an operative connection therefrom to the cinematograph apparatus, said connection comprising transmission gear automatically varying the driven speed with the load, said transmission gear comprising a gear wheel directly connected with the constant speed motor, planetary gears meshing therewith and carried by a driven member, together with eccentric masses rotating with said planetary gears and exerting a torque on

said driven member under the action of centrifugal force, in combination with electrically operated means for varying the load.

4. In combination with a cinematograph, 5 a constant speed driving motor, and an operative connection therefrom to the cinematograph apparatus, said connection comprising transmission gear automatically varying the driven speed with the load, said 10 transmission gear comprising a gear wheel directly connected with the constant speed motor, planetary gears meshing therewith and carried by a driven member, together with excentric masses rotating with said 15 planetary gears and exerting a torque on said driven member under the action of centrifugal force, in combination with manually-controlled electrically-operated means for varying the load.
- 20 5. In combination with a cinematograph, a constant speed driving motor, and an operative connection therefrom to the cinematograph apparatus, said connection comprising transmission gear automatically 25 varying the driven speed with the load, said transmission gear comprising a gear wheel directly connected with the constant speed motor, planetary gears meshing therewith and carried by a driven member, together 30 with excentric masses rotating with said planetary gears and exerting a torque on said driven member under the action of centrifugal force, in combination with brake means for varying the load.
- 35 6. In combination with a cinematograph, a constant speed driving motor, and an op-

erative connection therefrom to the cinematograph apparatus, said connection comprising transmission gear automatically 40 varying the driven speed with the load, said transmission gear comprising a gear wheel directly connected with the constant speed motor, planetary gears meshing therewith and carried by a driven member, together with excentric masses rotating with said 45 planetary gears and exerting a torque on said driven member under the action of centrifugal force, in combination with means for braking a driven member of the cinematograph to vary the load.

7. In combination with a cinematograph, a constant speed driving motor, and an operative connection therefrom to the cinematograph apparatus, said connection comprising transmission gear automatically 50 varying the driven speed with the load, said transmission gear comprising a gear wheel directly connected with the constant speed motor, planetary gears meshing therewith and carried by a driven member, together 55 with excentric masses rotating with said planetary gears and exerting a torque on said driven member under the action of centrifugal force, in combination with means for applying a braking action to the shutter 60 of the cinematograph to vary the load.

In testimony whereof I have signed my name to this specification.
